US00D610002S

(12) United States Design Patent
Frank

(10) Patent No.: US D610,002 S
(45) Date of Patent: * Feb. 16, 2010

(54) ORAL PRODUCT PACKAGING WITH SURFACE ORNAMENTATION

(75) Inventor: David Edward Frank, Cincinnati, OH
(US)

(73) Assignee: The Procter & Gamble Co., Cincinnati,
OH (US)

() Term: 14 Years

(21) Appl. No.: 29/327,098

(22) Filed: Oct. 30, 2008

(30) Foreign Application Priority Data

Apr. 30, 2008 (EM) 000927264

(51) LOC (9) Cl. 09-03

(52) U.S. Cl. D9/432

(58) Field of Classification Search D9/430-433,
